In connection with the aluminum ethane disulfonate.

Aluminum o-sulfo-benzoate having the structural formula

may be prepared by reacting the barium salt with aluminum sulfate in the same manner described in connection with the aluminum ethane disulfonate.

The foregoing detailed description is given for clearness of understanding only, and no unnecessary limitations should be understood therefrom, for some modifications will be obvious to those skilled in the art.

The following is an example of a cosmetic cream including aluminum methionate:

"Tegacid" regular	pounds	20
Stearic acid	do	4 1/2
White protopet	do	1/2
Distilled water	do	35 1/4
Glycerine	do	1 1/4
Gum tragacanth powder	do	1/4
Aluminum methionate (71-3/7% Sol.)	do	33 3/4
Formaldehyde (37% solution)	do	3/4
Perfume	ounces	3 1/2

"Tegacid" is the trade name for a mixture of glyceryl monostearate and a wetting agent presumably of the sulfated fatty alcohol compound type. "White protopet" is white petrolatum, U. S. P.

We claim:

As a new composition of matter, aluminum methionate.

JOHN EDWARD CHRISTIAN.
GLENN L. JENKINS.
